UNITED STATES PATENT OFFICE.

JOHN S. GILLIES, OF MANILA, PHILIPPINE ISLANDS.

PROCESS FOR MAKING FABRICS FROM FIBROUS PLANTS.

1,096,709.

Specification of Letters Patent.

Patented May 12, 1914.

Application filed December 28, 1912. Serial No. 739,129.

To all whom it may concern:

Be it known that I, JOHN S. GILLIES, a citizen of the United States, residing at Manila, Philippine Islands, have invented certain new and useful Improvements in Processes for Making Fabrics from Fibrous Plants; and I do hereby declare the following to be a full, clear, and exact description of the invention, such as will enable others skilled in the art to which it appertains to make and use the same.

The present invention relates to the manufacture of fabrics from the strands of fibrous plants, especially plants of the genus *Musa*, viz. the abaca plant, and has for its purpose to produce a fabric by uniting the fibers or strands in transverse layers as distinct from weaving said fibers or strands; and it is further proposed to incorporate in the fabrics so made a filling of rubber, or other similar substance, whereby to obtain a water-proof fabric which will serve the purpose of heavy canvas.

To these ends the invention consists in the novel steps constituting my process as well as in the improved resultant product, all as will be more fully hereinafter disclosed and particularly pointed out in the claim.

In carrying out the process the abaca leaves are initially treated by a process disclosed in my co-pending application, Serial Number 739,128, executed by me, of even date herewith and entitled Method of and apparatus for uniting the fibers of fibrous plants; wherein said abaca leaf sections have removed from the body portions thereof all extraneous matter and leaving the fibrous strands in an exposed and separated condition, and by a further step the end portions of said leaf sections are cleaned to leave the strands thereof in a partially exposed and separated condition. For a further detailed description of this process, reference may be had to my application above identified. The required number of abaca leaf sections or strips treated in the manner stated are arranged in transversely crossing layers after the manner illustrated in Figure 1 of the accompanying drawing, and the number of said strips or abaca leaf sections will be dependent upon the dimensions of the fabric to be made. A layer of adhesive, preferably cement, is interposed between the crossing sections and then said sections are subjected

to pressure by any suitable apparatus and thereafter left to solidify or harden. In this manner the entire fabric is built up and the resultant product will be found to have all of the qualities of fabrics heretofore made of this material wherein the fibers thereof are united by the weaving process, and the present process may be furthermore carried out more economically.

To the end that a fabric produced may serve in place of heavy canvas, the present invention proposes to incorporate in the fabric and in the process of making a filling of rubber, or other like gum, and which in the pressure step of the process is caused to unite intimately with the interstices formed by the crossing strands of the strips, as will be evident.

A step in the process for making the fabric is shown diagrammatically in the accompanying drawing wherein:

Fig. 1 is a top plan view showing two strips disposed to be united; Fig. 2 is a transverse sectional view thereof; Fig. 3 is a transverse sectional view showing the corresponding step when a filling of rubber is incorporated, and Fig. 4 is a top plan view showing a plurality of strand strips interlapped or united in the form of a fabric.

1 and 2 designate the crossed strips of abaca leaf sections whose fibers have been cleaned and separated in the manner stated, and whose end portions 3 and 4 respectively are cleaned and have the fibrous strands thereof partially exposed. By reason of this last mentioned provision, the strands of the body portion of the strips are held in their normal and relatively true relation, the reason for which will be apparent. A layer 5 of cement of any suitable kind is interposed between the strands 1 and 2 of the strips as indicated in Fig. 2, and the three layers, i. e., the strands 1 and 2, and cement 5 are united by compression. In this manner the required number of transversely arranged strips are united for the manufacture of the fabric of the required dimensions.

In the modified construction shown in Fig. 3, the steps of procedure are the same excepting that an intermediate filler consisting of a layer of rubber 6 is interposed between the cement layers 5 and in this case also the fabric is built up of the required number of strips for producing the single

sheet of water-proof fabric which, as stated, will serve as a substitute for the present used heavy canvas. Fig. 4 illustrates the method of uniting a plurality of strips or strands by interlapping the same. This arrangement is particularly adapted when it is desired to make a fabric for use as rubber belting, rubber clothing, tarpaulins, and linoleum. In making up such fabrics it is proposed to first place a sheet of woven cloth, preferably of abaca fiber, then cover the same with a sheet made of interlapped sections, as shown in Fig. 4, and the whole is then covered by another layer of woven cloth, when they are all joined together by an adhesive preferably containing rubber; or the same may be sewn together.

It is obvious that those skilled in the art may vary the details of the process without departing from the spirit of my invention, and therefore I do not wish to be limited to

the above disclosure, except as may be required by the claim.

What I claim is:—

The process of producing fabrics from the fibrous strands of leaves of plants of the genus *Musa* which consists in stripping sections of said leaves intermediate the ends thereof to expose and separate the fiber strands, and treating the ends of said sections to partially expose and separate said strands; disposing said stripped sections into transversely crossing layers; and uniting said layers under pressure with an intermediate layer of adhesive, substantially as described.

In testimony whereof, I affix my signature, in presence of two witnesses.

JOHN S. GILLIES.
